UNITED STATES PATENT OFFICE.

JOHN G. DORWARD, OF SAN FRANCISCO, CALIFORNIA.

DOUBLE-ACTING DEEP-WELL PUMP.

959,321.

Specification of Letters Patent.

Patented May 24, 1910.

Application filed July 26, 1909. Serial No. 509,483.

To all whom it may concern:

Be it known that I, JOHN G. DORWARD, a citizen of the United States, residing at the city and county of San Francisco and State 5 of California, have invented new and useful Improvements in Double-Acting Deep-Well Pumps, of which the following is a specification.

My invention relates to a double-acting 10 pump, which is especially desirable for pumping in deep wells, and particularly those having tubular casings of limited area.

It consists of a pair of pump heads connected together by concentric tubing, the 15 inner one of which forms a pump cylinder within which a plunger is movable, and the outer one forms a channel for the passage of the water.

The pump heads are formed with di- 20 visional diaphragms having a plurality of passages surrounding the central core, half of these ports or passages being utilized for suction during one stroke, and the other half to pass the water from the pump cylinder to the discharge pipe and to the surface.

My invention also comprises details of construction and combination of parts which will be more fully explained by reference to the accompanying drawings, in which—

30 Figure 1 is a vertical section. Fig. 2 is a transverse section taken on the line $x-x$ Fig. 1. Fig. 3 is a similar section on line $y-y$ Fig. 1. Fig. 4 is a section on line $z-z$ of Fig. 1. Fig. 5 is a section on line $v-v$ 35 Fig. 1.

In the usual construction of double-acting pumps, it is common to employ either a hollow piston rod, or separate exterior discharge pipes.

40 In the first construction it is difficult to provide a piston rod of sufficient area to properly carry the water without too much friction; and in the latter construction the exterior discharge pipes occupy too much 45 space in the limited area usually found in deep well casings.

It is the object of my invention to provide a pump which may be readily inserted into, and removed from the well casing; said 50 pump having an ample pumping cylinder, and a conducting passage of sufficient area to dispose of the water, and to deliver it to the upwardly extending discharge pipe.

My pump consists of two heads $a-b$ of

a diameter such as will allow them to be 55 introduced into the well casing C. These heads are connected by an exterior cylinder 34, and an interior cylinder 33 which is concentric with the exterior cylinder. These cylinders may be screw-threaded at the ends 60 and fit into corresponding screw-threaded portions of the pumping-heads.

The plunger 17 is here shown consisting of four brass spiders, and four cup-leathers which are held in place by nuts on the plunger-rod 49. The cup-leathers are so faced that two of them operate on the up stroke, and two on the down stroke of the pump. The plunger-rod extends through the center of the two pump-heads, and upward within 70 the discharge pipe 37 to any desired point of discharge. The whole of the pump may be submerged in the water so that water may be alternately admitted from above and below during the pumping action.

In Fig. 2 I have shown the upper part of the upper pump-head a as having three ports, here marked A, C and E. These ports A, C and E are designed to admit water into the upper part of the upper head on 80 the down stroke of the plunger 17. This water passes down, as shown by the arrows, until it reaches the diaphragm 2, shown in cross section in Fig. 3. At this point the water is deflected inwardly, and into a 85 chamber 4 inside of the pump-head a . The diaphragm or partition 5 forms the upper portion of this chamber, and the spider 7 the lower portion. The diaphragm has a tapering periphery, and fit in the corre- 90 sponding taper of the inside of the pump-head as shown. The other diaphragms, to be hereafter described, are formed in the same manner, both for the upper and the lower head, and each of them is fitted with 95 the same taper so that when it is necessary to withdraw the interior portion of the pump for any reason, it may readily be done by pulling up on the plunger-rod.

The nut 50 at the bottom of the plunger- 100 rod 49 contacts with the lowermost valve-seat 24 and the nut 47 above the plunger with the corresponding valve-seat of the upper head, and the diaphragms and spiders, being connected as hereinafter described, all 105 may be lifted out, leaving the exterior portions of the pump-heads, and the connecting tubes in position.

In order to allow the parts to move smoothly, and particularly prevent the plunger cup-leathers from catching the inner portions of the pump-head, between the various beveled seats are enlarged tapering sides, as shown at 60, these tapering portions serving to guide the parts as they are removed or again inserted, and insuring their passing properly to their seats.

10 The diaphragm or partition 5 previously mentioned in the upper head is connected with the spider 7 below the chamber 4 by a sleeve 6 through which the plunger-rod moves. This sleeve may be screw-threaded 15 at the ends or otherwise constructed to unite the diaphragm and the spider. This spider serves as a seat for the valve 8. This valve is pressed upwardly by a spring 9, and normally closes the openings through the 20 spider.

The water which passes into the chamber 4 on the downward stroke of the plunger 17 acts, by reason of the vacuum thus produced, to open the valve 8 against the pressure of 25 the spring 9, and to allow the water to pass through, thence out through the ports 13, connecting with the ports A', C', and E', below the diaphragm 2. The water passing down through these ports again enters 30 the interior and the pump cylinder through ports 14, and the upper end 15 of the pump cylinder above the plunger, thus completing the suction and filling the upper part of the cylinder. The lower part of the pump cylinder 35 being already filled by the upper stroke of the plunger, this water will be forced downwardly, and will pass out through the port 18, which leads into three ports G, I and K, in the exterior of the 40 pump head b. From these ports it passes through the ports 19, and enters the chamber 20. The lower part of this chamber is closed by a valve 21, closing on the seat in the spider 24, and maintained in closed position by a spring 22.

The upper portion of the chamber 20 is formed by a partition or diaphragm 23 across the inside of the lower pump-head, and above the spider 24. These two parts 50 23 and 24 are connected by a sleeve 25, through which the plunger-rod is movable. The valve 21 closing on its seat, the water in the pump-cylinder is forced down through a spider 26, and this opens a valve 27, which is 55 closed upwardly against the spider, and is normally maintained closed by a spring 28, and from the pressure and weight of the water from the discharge pipe. The downward stroke of the plunger being superior to 60 this pressure opens the valve 27, and the water then enters the chamber 29. This chamber is formed by the spider 26 and the partition 23, the two being united by a sleeve

30 through which the plunger-rod passes. From the chamber 29 the water is forced 65 through the ports 31, and passes through the alternate ports H, J and L, thence into the space 32 formed between the concentric tubes 33 and 34; thence upwardly and through ports 35 in the upper head. These 70 ports lead into the ports B, D and F through which the water passes, thence through the ports 36, and into the discharge pipe 37. This completes the action of the pump on the down stroke. 75

When the plunger 17 moves upwardly from the bottom of the pump within its cylinder 33, the suction draws the water through the lower spider 24; overcoming the pressure upon the valve 21, the water enters 80 the chamber 20. From this chamber the water passes through ports 19 which lead into the ports G, I and K, and passes thence through the ports 18 which lead into the pump cylinder below the plunger. This 85 completes the suction on the up stroke.

The discharge of the water which has been drawn into the cylinder above the plunger 17, and during its downward movement, is effected through the ports 14, and 90 the ports A', C' and E', thence through the ports 13, closing the valve 8. The water in the cylinder then acts by passing through the spider 38 to open the valve 39, which is normally held closed by a spring 41, and the 95 pressure within the discharge pipe. Water passing the valve 39 enters the chamber 40. This chamber is formed between the spider 38 and the solid partition or diaphragm 11, and these two are connected by a sleeve 42 100 through which the plunger-rod passes. From the chamber 40 the water passes through ports 43 which lead into the ports B, D and F, previously mentioned. The water passes through these ports, thence 105 through the port 36, and into the discharge pipe 37, and to the surface. This completes the action of the pump on the up stroke.

The plunger-rod 49 has a packing-box 45, which screws down upon the upwardly extending portion of the partition 5, and a packing 46 is thus retained in place. This packing prevents the water from following the plunger-rod 49 through the diaphragm 5, and its connections. 110

Nuts 47 and 48 serve to clamp the plunger sections together. The nut 48 may be made sufficiently long to allow the tail rod 49 to screw into the nut. This tail rod passes through the diaphragm 23 and spiders 24 120 and 26, and has a nut 50 upon the lower end as previously described.

When it is necessary to overhaul the plunger-rods and cup leathers on the plunger, the pump rod is pulled up, and the 125 plunger 17 brings the whole interior of the

pump, that is to say the parts 38, 11, 7, 5, and the parts 24, 23, 26 to the surface. This includes all the valves and working parts, and leaves the pump cylinder and discharge pipe in position.

5 51 is a stuffing-box gland which clamps the packing 52 in place around the tail rod 49, and this keeps the water from following the rod through the members 23, 24 and 26.

10 Having thus described my invention, what I claim and desire to secure by Letters Patent is—

15 1. The combination in a pump, of upper and lower heads and an intermediate cylinder, said heads and cylinder being formed of concentric spaced cylinders and each of said heads having a plurality of exterior ports and an interior chamber, and a closed partition within said chamber, a valve for 20 admitting water through the head, and a plunger movable within the inner cylinder, the space between the cylinders forming a discharge passage from the lower head.

25 2. In a pump, the combination of a cylinder and a concentric head spaced therefrom to form a water passage, said head having a lateral opening, connecting with said space and having an interior chamber with which the opening connects, a horizontal partition 30 between the cylinder and head said head having a water passage through it, and said head having a lateral opening below said partition connecting with the space between the head and cylinder, a valve controlling 35 the water passage through the head, and a plunger below the valve and connecting with the space between the head and cylinder, said cylinder having a discharge passage.

40 3. The combination in a pump, the upper and lower heads and an intermediate connection, cylinders surrounding the heads and connection and forming a water passage therebetween, one of said cylinders having a horizontal partition with a central water 45 passage and said heads having lateral openings above and below the partition connecting with the space between the heads and cylinders, other partitions extending transversely across the heads, and valves above 50 and below said second partitions and controlling the passage of water through the lateral openings in the heads, and a piston operable in said intermediate connection.

55 4. The combination in a pump, of upper and lower valve containing heads and an intermediate connection with a plunger movable therein, said heads and connection being formed of concentric spaced cylinders with lateral openings therethrough, and said 60 inner cylinder having a closed chamber connecting with said openings, closed partitions extending across the space between said cylinders, a valve controlling the discharge

from said chamber and delivering water into the space at the other side of the partition, 65 and a main discharge pipe with which the water passages communicate.

5 The combination in a pump of outer and inner concentric tubes, a plunger reciprocable in the inner tube, said plunger having a plurality of parallel spiders and oppositely turned cup leatherheads formed of inner and outer cylinders and to which opposite ends of the tubes are secured, ports and channels formed in the heads and connecting with the annular space between the two, spring-pressed valves by which said ports are secured, and closed partitions extending across the space between the inner and outer cylinders of an intermediate portion of the heads, said heads having an inner chamber connecting with said space, whereby reciprocation of the plunger produces alternate suction and ejection of water through each of the heads.

70 6. The combination in a pump of a head having a plurality of exterior ports and an interior chamber, closed partitions located within the inner chamber, seats with upwardly and downwardly opening valves, and 80 passages connecting the interior space with the alternate exterior ports, a plunger-rod extending through the partitions and spiders, and a plunger with which it is connected.

75 7. The combination in a pump of an upper head having a plurality of exterior ports, an interior chamber with partitions, valve seats and valves closable upon said seats, passages opening through the valve 100 seats, and communicating respectively with one set of the exterior ports, and the other with the alternate ports, a discharge pipe leading from the upper end of the head, a pump cylinder, a plunger fitting therein, 105 and a plunger-rod extending through the valves and partitions.

8. In a pump, a pump head having a series of ports within the outer shell, a partition or diaphragm fitting the upper part of the 110 inner shell, a valve seat and a tubular connection between it and the diaphragm, a downwardly opening valve closable upon said seat, a second partition below said valve, a second valve seat below said second partition having an upwardly opening valve, 115 openings connecting the interior shell with alternate of the exterior ports, and other ports connecting the interior of the shell with the other of the exterior ports, a pump 120 cylinder, a plunger fitting therein, and a pump rod extending upwardly through the valve seats and diaphragms.

9. In a pump, a pump head having a plurality of ports or channels within the exterior shell, an interior shell, alternate trans-

verse diaphragms and valve seats closable in opposite directions upon said valve seats, tubes connecting the diaphragms and valve seats into a single structure, a plunger rod 5 extending through said tubes, a pumping cylinder, a plunger movable within said cylinder having a nut upon the upper side, said nut contacting with the lower valve seat, whereby the connected diaphragms and valve 10 seats may be removed in unison by lifting upon the plunger-rod.

10. In a pumping apparatus, a pump head including an exterior and interior shells, with a plurality of ports located between 15 them, passages opening in said ports into the interior shell, transverse diaphragms and alternating valve seats, with upwardly and downwardly opening valves, said diaphragms and valve seats having tapering 20 peripheries, and corresponding tapering seats in the inner shell to receive and hold said parts in position.

11. The combination in a pump, of a pumping cylinder, a plunger reciprocable 25 therein, a pump head having exterior and interior shells with a plurality of intermediate ports, interspaced partitions and valve seats having tapering peripheries, corresponding tapering seats in the inner shell 30 in which said partitions fit, spring-pressed valves opening in opposite directions, passages between the valve chambers and the exterior ports through which water may be transmitted, a discharge pipe and an inlet 35 passage communicating with the upper ports, and a plunger rod guided and movable through the central portions of the diaphragms and valve seats, and through their connecting sleeves.

40 12. The combination in a pump, of a pumping cylinder, a plunger fitting therein having an upwardly extending pump rod, a pump head to which the upper end of the cylinder is connected, said head including an 45 outer and an inner shell, with a plurality

of ports between said shells, alternate partitions and valve seats with connecting tubes, the peripheries of said partitions and valve seats being tapered, correspondingly tapered surfaces within the inner shell which coact 50 with the surfaces of the diaphragms and valve seats to retain them in position, enlargements of the inner shell between said seats, said enlargements having inclined surfaces to serve as guides in the removal and 55 replacement of the plunger, the partitions and the valve seats.

13. The combination in a pump, of a pumping cylinder and exterior concentric shell, with a water passage between the two, 60 an upper pump head including an outer and inner shell with which the pump cylinder and exterior tube are respectively connected, a plurality of independent ports between the outer and inner shells of the pump head, 65 connected alternate partitions and valve seats removably fitting seats in the interior of the inner shell, and oppositely opening valves with passages connecting with the exterior ports, a second head connected with 70 the lower end of the pump cylinder and the exterior tube respectively, said lower head having valve seats at opposite ends, an intermediate partition and oppositely opening valves with connecting sleeves, said valve 75 seats and partition being removably fitted to the inner shell of the lower head, a plunger-rod extending centrally through said valve seats and partitions, and means carried by the plunger-rod to contact with the 80 lowermost valve seats whereby they may all be lifted above the pump cylinder.

In testimony whereof I have hereunto set my hand in the presence of two subscribing witnesses.

JOHN G. DORWARD.
